CLAIM

The ornamental design for an adjustable reach assist foot platform, as shown and described.

DESCRIPTION

FIG. 1 is a front perspective view of an adjustable reach assist foot platform of the present invention;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken lines in FIGS. 1–7 depict environmental subject matter and form no part of the claimed design.
